AUTOMOBILE BUMPER

Frederick Reynolds and William B. Pratt, Birmingham,
Mich., assignors to Chrysler Corporation, Highland
Park, Mich., a corporation of Delaware

Filed July 1, 1960, Ser. No. 61,187

Term of patent 7 years

(Cl. D14—6)

Fig. 1 is a front view of an automobile bumper embodying our new design;

Fig. 2 is a top plan view thereof;

Fig. 3 is a side elevational view thereof;

Figs. 4 and 5 are sectional views taken on the lines 4—4 and 5—5, respectively, of Fig. 1; and

Fig. 6 is a sectional view taken on the line 6—6 of Fig. 2.

We claim:

The ornamental design for an automobile bumper, substantially as shown.
